THEREFOR

Goichi Matsui, 1089-1 Nagasawa, Reiho Village,
Mie Prefecture, Japan

Filed July 28, 1966, Ser. No. 3,245

Term of patent 14 years

(Cl. D9—188)

FIG. 1 is a front perspective view of a package of candles and holders therefor embodying my new design, the candles and holders being held in place by a press fit relationship or the like;

FIG. 2 is a front perspective view with the candles and holders removed in order to illustrate the compartments of the package;

FIG. 3 is a rear perspective view with some of the candles and holders removed in order to illustrate the nature of the compartments of the package;

FIG. 4 is an exploded sectional view taken on the line 4—4 of FIG. 1; and

FIG. 5 is a sectional view taken on the line 5—5 of FIG. 1.

I claim:

The ornamental design for a package of candles and holders therefor, substantially as shown.
